WILLIAM G. SCHAEFFER, OF READING, PENNSYLVANIA, ASSIGNOR, BY MESNE ASSIGNMENTS,
TO READING STANDARD COMPANY, A CORPORATION OF PENNSYLVANIA

MUFFLER CUT-OUT.

No. 880,471.

Specification of Letters Patent.

Patented Feb. 25, 1908.

Application filed April 30, 1906. Serial No. 314,405.

To all whom it may concern:

Be it known that I, WILLIAM G. SCHAEFFER, citizen of the United States, residing at Reading, in the county of Berks and State of Pennsylvania, have invented certain new and useful Improvements in Muffler Cut-Outs, of which the following is a specification.

This invention has relation to cut-outs for mufflers, and it consists in the novel arrangement of its parts as hereinafter shown and described.

Strictly speaking, the cut-out is not a portion of the muffler but affords a means for connecting or communicating the exhaust pipe of an engine with a muffler. The cut-out is in the form of a fitting and is provided at one end with a port for connection with the exhaust pipe and at its opposite end with a port against which a valve is designed to operate. The fitting is provided at a point intermediate of its ends with a muffler port for connection with a muffler. The channel through the fitting is distorted or inclined slightly away from the lateral port, and at 25 its lower portion is curved toward the said port in order to relieve the valve at the lower end of the fitting from excess pressure when closed.

In the accompanying drawing, the figure 30 is a side elevation of the fitting connected up with an exhaust pipe and a muffler.

The muffler 1 is of any usual form and the fitting 2 is interposed between the said muffler and the exhaust pipe 3. The upper end of 35 the fitting 2 is non-circular, as at 4, and is provided with an opening which communicates with the pipe 3. At its opposite end the fitting is provided with an opening 5. Said opening is provided with a seat 6. The 40 lugs 7 are located upon the outer side of the fitting 2 and the shank 9 is pivoted to said lug by means of a pin 8. The valve 10 is mounted upon the shank 9 and is adapted to close against the seat 6 of the opening 5.

The element 11 is attached at one end to the shank 9 and is adapted, when drawn, to hold the valve 10 closed against the seat 6. One end of the spring 12 is attached to a stationary point and its other end is attached to the shank 9. The said spring is under tension and has a tendency to hold the shank 9 and the valve 10 away from the seat 6. All of the openings of the fitting are of substantially the same lateral dimensions, and the channel through the fitting is slightly distorted or inclined away from the lateral opening of the fitting, and at its lower portion is curved toward the said lateral opening. The object in providing the inclined channel as specified is to relieve the valve 10 and shank 9 from the direct pressure or force of the exhaust when the said valve is closed, and the said exhaust is introduced into the muffler. Thus the valve will not be vibrated against its seat with injury to the valve and seat. 65

What is claimed is:—

A muffler cut-out comprising a fitting having parallel inlet and outlet ports, a swinging valve adapted to close the outlet port, a muffler port located between and substantially perpendicular to said inlet and outlet ports, all of said ports being of substantially the same area, said fitting having a channel leading from the inlet port to the outlet ports, said channel being bent at an intermediate point and inclined at an angle to said parallel ports and then curved arcuately into alignment with said muffler port, whereby the outlet port is relieved of the direct pressure or impact of the exhaust entering the inlet valve. 75

In testimony whereof I have signed my name to this specification in the presence of two subscribing witnesses.

WILLIAM G. SCHAEFFER.
